UNITED STATES PATENT OFFICE

ERNEST O. FREDERICS, OF NEW YORK, N. Y., ASSIGNOR TO E. FREDERICS, INC., OF NEW YORK, N. Y., A CORPORATION OF NEW YORK

DESIGN FOR A HAIR-DRYING HOOD

Application filed November 9, 1929. Serial No. 33,392. Term of patent 14 years.

To all whom it may concern:

Be it known that I, ERNEST O. FREDERICS, a citizen of the United States, residing at New York city, county and State of New York, have invented a new, original and ornamental Design for Hair-Drying Hoods, of which the following is a specification, reference being had to the accompanying drawing, forming a part thereof.

Figure 1 is a perspective view of hair drying hood, showing my new design; and Fig. 2 is a front view thereof.

I claim:

The ornamental design for a hair drying hood as shown.

ERNEST O. FREDERICS.
